PRESSER-FOOT LIFTER FOR SEWING MACHINES

Richard Kaier, deceased, late of Cranford, N. J.,
by Eleanor C. Kaier, executrix, Cranford, N. J.,
assignor to The Singer Manufacturing Company,
Elizabeth, N. J., a corporation of New Jersey

Original application July 9, 1937, Serial No.
152,707. Divided and this application November 9, 1939, Serial No. 303,631

4 Claims. (Cl. 112—237)

This invention relates to sewing machines and more particularly to mechanism for raising and lowering the presser-foot of a sewing machine, and has for its objective the provision of improved means carried by and extending through an oil receptacle and so designed that the presser-foot can be raised quickly and with the minimum of effort.

With the above and other objects in view as will hereinafter appear, the invention comprises the devices, combinations and arrangement of parts hereinafter described in connection with the accompanying drawings which illustrate a preferred embodiment of the invention and in which:

Fig. 1 is a rear elevation, partly in section, of a machine embodying the invention.

Fig. 2 is a vertical sectional view taken along the line 2—2 of Fig. 1.

As shown in the drawings 10 represents the bed which supports a bracket-arm 11 terminating in a hollow head 12. Journaled in the head 12 is the usual needle-bar 13 and presser-bar 14 the latter of which carries a presser-foot 15 adapted to cooperate with the usual feed-dog 16. For a detailed description of the feeding and stitch-forming mechanism of the machine, reference may be had to Patent No. 2,206,285, dated July 2, 1940, and issued to R. Kaier on an application, filed July 9, 1937, of which this application is a division.

An oil-reservoir 17 is secured beneath an opening 18 in the table-top 19 by means of the bolts 20. Carried by the reservoir 17 is a layer of vibration and sound-absorbing material 21 upon which rests the downwardly extending flange 22 of the bed 10. The bed 10 and the reservoir 17 together form an oil-tight enclosure for the operating parts of the machine.

The reservoir 17 is die cast and is formed with a depending lug 23 and a laterally extending arm 24 the lower ends of which are apertured to receive a rock-shaft 25. Fixed to one end of the shaft 25 by a set-screw 26 is a collar 27 formed with a laterally projecting portion 28 which is adapted to engage the lug 23 and fixed to the other end of the shaft by a set-screw 29 is a collar 30 formed with a lateral extending portion 31 which is adapted to engage the arm 24. The portions 28 and 31 act as stops to limit the movement of the rock-shaft 25 in both directions of movement.

Fixed to the shaft 25 is a T-shaped member 32 which carries a depending rod 33 having a knee-pad 34 adjustably secured thereto by the set-

screw 35. Adjustably secured to the shaft 25 by the set-screw 36 is an arm 37 formed with a cup-shaped depression 38 which receives the lower end of a push-rod 40. The rod 40 extends through a boss 41 formed on the oil receptacle 17 and the upper end of the rod cooperates with a lever 42 pivoted at 43 to the depending arms 44 of the bracket 45 which is fixed to the under side of the bed 10. It will be noted that the upper end 10 of the boss 41 extends well above the bottom of the reservoir 17 and between the ends of the rod 40 there is provided an inverted cup-shaped oil-guard 47. The level of the oil in the reservoir is well below the top of the boss 41, and when oil 15 is splashed on the upper end of the rod 40 or the guard 47 the oil runs over the edges of the cup-shaped guard and drops back into the reservoir. This permits the rod 40 to be freely mounted in the boss 41 and prevents the oil in the reservoir from running down the rod.

The other end of the lever 42 has a ball-and-socket connection 48 with a pull-rod 49 and the upper end of this rod has an adjustable ball-and-socket connection 50 with the presser-foot 25 raising lever 51 which is pivoted to the bracket-arm of the machine at 52.

Coiled about the pivot 52 is a spring 53 which has one of its ends 54 bent at right angles and extending into an aperture in the bracket-arm. 30 The other end 55 of the spring reacts against the lever 51 and constantly urges it in a clockwise direction about the pivot 52.

The end 56 of the lever 51 carries a rod 57 which extends into the hollow head 12 and is operatively connected with the spring depressed presser-bar 14 by a link 58 in the usual and well known manner.

From the foregoing it will be understood that when the rod 33 is moved to the left, as viewed in Figure 1, the arm 37 will raise the rod 40 and shift the lever 42 about its pivot 43. This movement of the lever 42 pulls down on the rod 49 and shifts the lever 51 in a counterclockwise direction about its pivot 52 and the end 56 of the lever 51 through the rod 57 and link 58 raises the presser-bar 14 and presser-foot 15.

Having thus set forth the nature of the invention, what is claimed herein is:

1. In combination with an oil-reservoir provided with depending supporting members and a sewing machine resiliently supported upon the oil-reservoir, a rock-shaft journaled in said depending supporting members, said sewing machine having a presser-bar, manual means for actuating said rock-shaft, a rod slidable through

a boss formed on said reservoir and having an operative connection with said rock-shaft, an oil-guard carried by said rod and overlying said boss, and mechanism for operatively connecting said rod to the presser-bar of the sewing machine.

2. In combination with an oil-reservoir provided with depending supporting members and supported by a table and a sewing machine resting on the oil-reservoir and having a presser-bar, a rock-shaft journaled in said depending supporting members, manual means for actuating said rock-shaft, an arm on said shaft, a push-rod adapted for actuation by said arm and extending into said reservoir, said push-rod being confined to a right line movement, a lever carried beneath the bed of the machine and in operative engagement with said push-rod, and means connecting said lever to the presser-bar of the sewing machine whereby said presser-bar may be raised and lowered.

3. In combination with a supported reservoir adapted to contain a quantity of oil and a sewing machine resting on the reservoir and lubricated by the oil in the reservoir, said sewing machine having a presser-bar, a plurality of bearing lugs formed on said reservoir, a shaft journaled in said lugs, manual means for rocking said shaft, a

vertical rod slidable through an aperture in the bottom of the reservoir and having one of its ends in operative engagement with an arm carried by said shaft, means for preventing oil from escaping from said reservoir along said rod, and mechanism connecting the end of the rod which is within the reservoir with the presser-bar of the sewing machine.

4. In combination with a supported reservoir adapted to contain a quantity of oil and a sewing machine resting on the reservoir and lubricated by the oil in the reservoir, said sewing machine having a presser-bar, a plurality of supporting members formed on the under side of said reservoir, a shaft journaled in said members, a rod movable endwise through a boss formed on the bottom of the reservoir, a guard on said rod for preventing oil from running down the rod, means connecting one end of the rod with the presser-bar of the machine, and manual means operatively connected with the other end of the rod for raising and lowering the presser-bar from a point below the oil-reservoir.

ELEANOR C. KAIER,
*Executrix of the Last Will and Testament of
Richard Kaier, Deceased.*
